TYPEWRITING MACHINE

Charles Walker, Syracuse, N. Y., and Willard H. Wade, Washington, D. C., assignors to L. C. Smith & Corona Typewriters, Inc., Syracuse, N. Y., a corporation of New York

Application June 17, 1943, Serial No. 491,086

6 Claims. (Cl. 197—91)

The invention relates to improvements in typewriting machines and, more particularly, to improvements in power actuated back spacing means for such machines.

The principal object of the invention is to provide in a typewriting machine improved means for reversely stepping one letter space a travelling carriage or support which is normally controlled by an escapement or other means to move in the opposite direction longitudinally of the printing line of the machine one letter space per character typed or per operation of a letter spacing bar of the machine. The carriage or support in most kinds of typewriting machines is a paper carriage, but in some kinds of machines it carries the type bars or other impression making means of the machine instead of the paper.

Further important objects of the invention are to provide an improved back spacing mechanism for typewriting machines whereby the force for reversely stepping the carriage is taken from a shaft or other rotary element which is constantly rotated at high speed, as by an electric motor, while the machine is in use, and to provide, in such a back spacing mechanism, means positively connective with the shaft or element for a single revolution only of the shaft or element to first impart a fixed back spacing throw to a reciprocal back spacing element or dog by power from said shaft or element and to then impart a biased restoring movement (as by spring means) to said back-spacing element or dog to a normal idle position during each cycle of connection of said means with said constantly rotating shaft or element.

Other objects and advantages of the invention will appear from the following description of a preferred embodiment of the invention shown in the accompanying drawings.

In the drawings,

Figure 1 is a fragmentary top plan view of a typewriting machine equipped with a back spacing mechanism embodying the invention, the back spacing mechanism being shown in idle condition and certain parts being omitted for greater clarity of illustration of certain features of the invention.

Figure 2 is a fragmentary vertical sectional view approximately on the line 2—2 of Figure 1.

Figure 3 is a detail sectional view on the line 3—3 of Figure 2.

Figure 4 is a detail sectional view on the line 4—4 of Figure 1.

Figure 5 is a view similar to Figure 4, but showing the back spacing mechanism in operation.

Figure 6 is a detail sectional view on the line 6—6 of Figure 1.

The drawings illustrate the improved power actuated back spacing mechanism as incorporated in a preferred form in an otherwise known typewriting machine, namely, the series 1 Super Speed L C Smith typewriting machine.

The machine has a suitable stationary main framework 10 upon which the usual platen carriage 11 is mounted in the usual manner for advance and return horizontal travel transversely of the machine, the usual roller platen 12 being journaled in the carriage and extending horizontally transversely of the machine. The carriage 11 is advanceable one letter space per letter printed or per operation of the space bar of the machine as usual by power from the usual spring drum (not shown) under control of the usual escapement mechanism.

In the known machine the means whereby the letter space advance of the carriage is effected includes the usual feed rack 13 fixed to the carriage and extending horizontally transversely of the machine, the usual feed pinion 14 meshing with said rack, the usual escapement wheel 15, the usual fore and aft extending shaft 16 journaled in the framework 10 and to which said wheel and pinion are fixed, the usual escapement dog rocker 17 oscillable about the fixed horizontal pivot 11a which extends transversely of the machine, and the usual pair of escapement dogs 18 and 19 which alternatively engage with teeth of the escapement wheel in the normal and rocked positions of the dog rocker in the usual manner, the dog 18 being the usual stepping dog over which the escapement ratchet wheel 15 is adapted to ratchet as usual when the carriage is back spaced.

The known machine also has a back spacing element or dog 20 of bellcrank form pivotally connected by a pivot 21 (extending fore and aft of the machine) to the upper end of an arm 22, the arm 22 being pivotally held at its lower end to the framework 10 by a fore and aft extending pivot 23. The dog 20 has an arm pendent from its pivot and an arm extending leftward from its pivot, the latter arm having a reduced left hand end portion 20a slidably guided in a vertical slot 24 in framework 10. Slot 24 is closed at its lower end. The usual return spring 26 is connected to framework 10 and arm 22 to normally hold the dog 20 and arm 22 in the idle position shown in Figure 3. In this idle position of dog 20, the usual rightwardly facing stop shoulder 20c, formed on the dog above pivot 21, is engaged with the usual stop lug 27 on the

framework 10, the end portion 20a of the dog is seated on the bottom wall of slot 24 with the usual upstanding rack teeth 25 of the dog disengaged from the teeth of the feed pinion 14, and the usual cam edge 20b of the dog is retracted rightward from slot 24. Cam edge 20b extends downward and rightward from portion 20a of the dog. The usual link 101, which extends transversely of the machine, is pivoted at its left hand end at 102 to the pendent arm of dog 20 and is pivoted at its right hand end at 103 to the upper end of the usual normally upstanding arm 104. The arm 104 and the usual bellcrank 105 are both loosely pivoted on a fore and aft extending pivot 106 carried on framework 10. The bellcrank has an upwardly extending arm which is adjustably connected as usual to arm 104, said arm of the bellcrank having a slot 105a through which extends the shank of a clamping screw 107 which is threaded into arm 104 and clamps the arm and bellcrank to rock as a unit about pivot 106.

The improvements constituting the present invention are illustrated as embodied in power means for actuating the aforesaid back spacing dog of the known machine through the aforesaid bellcrank and will now be described.

A power driven shaft 36, which extends horizontally transversely of the machine in the main framework 10 adjacent the rear end of the machine, is journaled in said framework at 37 and 38 and is constantly rotated clockwise (as viewed in Figure 2) by suitable power means while the machine is in use. Preferably, as shown, this constant power drive of shaft 36 is effected by a small electric motor 39 mounted in the framework 10, which motor is constantly energized while the machine is in use and has a suitable speed-reducing driving connection 40 between its shaft 39a and the shaft 36. Small electric motors, such as employed in the machine shown, rotate at high speed. While shaft 36 is driven by the motor through a reduction gearing, it still is driven at a high speed, a speed of approximately 400 R. P. M. having been found satisfactory for back spacing operations.

A single cycle clutch mechanism of the single revolution type is provided for transmitting power from the shaft 36 to impart back spacing movement to the carriage, said clutch mechanism including a single control key 41 located in the keyboard of the machine. This clutch mechanism, which is of a special construction in the improved machine shown, will now be described.

The driving element of the clutch is a ratchet wheel 42 which is fixed on shaft 36 to rotate with the latter, and the driven element of the clutch is a ratchet dog 43 which is pivoted at 44 on a dog carrier 45 and is normally disconnected from the driving element. A suitable torsion spring 46 constantly tends to rock dog 43 about its pivot into engagement with the ratchet wheel 42 for driving of the dog 43 and its carrier 45 by said wheel around the axis of shaft 36 in clockwise direction as viewed in Figure 2.

The driving and driven elements of the single cycle clutch mechanism are engageable to rotate the driven element and the dog carrier solely and exactly 360 degrees about the axis of shaft 36 from a normal idle position in which said clutch elements are releasably disengaged and the dog carrier is releasably locked against rotation in both directions about said shaft axis.

A lever 51 is pivoted on a horizontal pivot 52

held to and extending transversely of the main frame 10, and said lever is biased by a return spring 53 to move to a normal idle position in which a stop finger 54 on said lever is urged forwardly of the machine against a fixed stop part 55 of the framework 10. At its upper end, said lever is provided with a laterally bent lug 56 for intercepting shaft-driven rotation of the dog carrier. Also pivoted on pivot 52 is a latch arm 57 between the free upper end of which and the lug 56 the reduced end portion 58 of the dog carrier is normally closely confined to latch the dog carrier in normal idle position against rotation in either direction. A spring 59 is connected to lever 51 and latch arm 57 to bias the latch arm to a normal latching position determined by a lug 60, which lug is formed on lever 51 for normal engagement therewith of the latch arm and to limit spring-urged movement of said arm. In the latched normal position of the dog carrier, the lug 56 on lever 51 is engaged with a tail portion 61 of clutch rod 43 to hold the nose of said dog out of engagement with the driving element (ratchet wheel 42) of the clutch.

25 A key lever 62 has an arm pendent from and pivoted on a fulcrum rod 63, and said lever has a normally horizontal arm which extends forward from the pendent arm, substantially midway the upper and lower ends of said pendent arm, and is provided adjacent its forward end with an upstanding stem portion on the upper end of which the control key 41 is fixed. The forwardly extending arm of the key lever is guided in one of a plurality of vertical guide slots 64 formed in a straight guide comb 65 which extends transversely of the machine and is fixed to the framework 10. Depression of the key 41 is limited by engagement of the forwardly extending arm of the lever with the closed lower end of its guide slot. The key lever, and the means hereinafter described positively connected therewith, are held in normal idle position by a return spring 66 which is connected with the framework and the pendent arm of the key lever 45 to yieldingly hold the key 41 in a normal elevated position in which a pendent stop lug 67 on the forwardly extending arm of the key lever is pressed forward against a straight return stop device 68 which extends horizontally transversely of the machine.

The fulcrum rod 63, preferably, is a straight rod which extends horizontally transversely of the machine to the rear of the keyboard, is fixed to framework 10, and crosses the slots of a straight horizontal row of vertical guide slots 69 formed in the machine framework, in one of which slots the upper end of the pendent arm of the key lever 62 is pivotally guided. Preferably, the key lever 62 is located adjacent the left hand side of the machine with key 41 located at the left hand end of the keyboard of the machine. The fulcrum rod 63 may also serve as the fulcrum rod for, and stop 68 as a return stop for, the type selecting key levers of key-controlled type bar actions for actuating the type bars (not shown) by power from shaft 36 in the manner and through the means disclosed in the application for United States patent of Charles Walker, filed November 26, 1943, Serial No. 466,989, and the dog rocker 17 may be actuated by means constructed as described in said application. The machine may also have its type bars (not shown) supported in a segment which is shiftable for case-changing by means disclosed in our application for United States patent filed February 9,

1943, Serial No. 475,264, and may have carriage return means and line spacing means constructed as disclosed in our application for United States patent filed May 20, 1943, Serial No. 487,686.

Journalized in the framework 10 substantially medially of the front and rear ends of the machine is a horizontal rock shaft 72 which extends transversely of the machine. Fixed on this shaft are two pendent rock arms 73 and 74, the arm 73 being substantially in fore and aft alignment with the pendent arm of key lever 62, and the arm 74 being substantially in fore and aft alignment with lever 51. A fore-and-aft extending and normally horizontal link 75 connects the lower end of the pendent arm of the key lever with the lower end of rock arm 73. To the lower end of rock arm 74 a fore and aft extending and normally horizontal tappet bar 76 is pivoted at its forward end at 78 for swinging movement in a vertical plane. Tappet bar 76 is constantly guided intermediate its ends in a vertical guide slot 77 in stop part 55 of framework 10 and is normally held rocked up against the closed upper end of slot 77 by the spring 53 which is anchored to the lever 51 and to the rear end of the tappet bar. To the rear of part 55 the tappet bar 76 is provided at its upper side with a rearwardly facing shoulder 79 which is normally located immediately forward of a laterally bent lug 80 formed on lever 51 below the fulcrum of said lever.

A mutilated pinion 47, loose on shaft 36 and located to the right of ratchet wheel 42, has its hub 47a extending through both the dog carrier 45 and an arm 48 and abutting the adjacent face of ratchet wheel 42. Arm 48 is fixed to the pinion hub 47a in a predetermined angularly adjusted position about the axis of the mutilated pinion 47, and the dog carrier 45 is fixed to said arm by a pin or rivet 49. The dog 43, dog carrier 45, arm 48 and mutilated pinion 47 are thus rotative with shaft 36 when dog 43 is engaged with ratchet wheel 42.

A lever 86 has its hub loosely journalized on shaft 36 and confined between the mutilated pinion 47 and the shaft bearing or journal 38, said lever having a forwardly extending arm and a rearwardly extending arm and being biased to move to a normal idle position in which a pin 87 on its rearwardly extending arm is seated on the upper edge of a stop lug 88 formed on framework 10. A segment rack lever 90 is pivoted intermediate its ends on the framework at 89 to rock in the same vertical plane extending fore and aft of the machine in which the mutilated pinion 47 is located, said segment rack lever having a toothed forward arm and also having a rear arm which is formed with a slot 91 which is radial to the fulcrum of the lever. The pin 87 is slidably engaged in slot 91 and contacts both longitudinal walls of said slot. The segment rack lever is freely movable about its pivot 89 past the non-toothed portion of the periphery of mutilated pinion 47, but the normal stationary positions of the rack lever and pinion are such that, upon each revolution of the pinion, said pinion will first mesh with the teeth of said rack lever and rock the rack lever and lever 86 counterclockwise, as viewed in Figure 2, and clockwise as viewed in Figures 4 and 5, through a predetermined angle of rotation determined by the number of teeth on the pinion, and will thereupon demesh with said rack lever before the pinion completes a single revolution and thus free both the rack lever and lever 86 for instant 75

return, under the influence of the hereinafter explained biasing force exerted thereon, to their normal idle positions during said single revolution of the pinion. Said demeshing of the rack lever and pinion preferably occurs (as in the construction shown) when the clutch element 43 and the pinion 47 have been rotated approximately one-half of a revolution from normal position.

Pivoted to the forward end of the forwardly extending arm of lever 86 at 94, to rock fore and aft of the machine, is a pendent arm 95. A spring 96 is connected with arm 95 and with a pendent extension of lever 86 to normally bias the rear arm of lever 86 down to engage pin 87 with lug 88. Spring 96 also constantly holds the arm 95 rocked rearward against the closed rear end of a fore and aft extending guide slot 98 in a part 99 of framework 10. The pendent arm 95 is formed at its lower end with a laterally bent lug 100 overlying tappet bar 76 and adapted, by the aforesaid rocking of the lever 86 from its normal idle position, to engage tappet bar 76 and swing it downwardly about its pivot 78 far enough to release lug 80 on lever 51 from shoulder 79 on the tappet bar.

From the foregoing, it is believed that the operation of the cyclic clutch will be obvious, but a cycle of operation thereof will be described. Upon full depression of control key 41, with the parts of the cyclic clutch mechanism in their normal idle position shown in Figures 1, 2 and 4, the tappet bar 76 is pushed rearwardly to rock lever 51 and latch arm 57 into the position shown in Figure 5, thus releasing the clutch dog 43 and its carrier 45, whereupon the dog 43 will be rocked by its biasing spring 46 into engagement with the driving clutch element 42, and the dog carrier and dog will then start a driven revolution about the shaft axis in a clockwise direction, as the parts are viewed in Figure 2, and counterclockwise direction, as the parts are viewed in Figures 4 and 5. This driven movement of the dog and dog carrier imparts a like driven movement to the mutilated pinion 47, which pinion thereupon first meshes with the segment rack lever 90, rocks said lever 90 through a fixed arc from its normal idle position, and then demeshes from the rack lever, all before the first revolution of the driven element 50 of the clutch is completed, and will thereafter remain demeshed from the rack lever until the next cycle of operation of the clutch.

The aforesaid fixed extent of rocking movement imparted from the driven element of the clutch to rack lever 90 also rocks lever 86 through pin 87 a fixed extent from the normal idle position of said lever 86, thus depressing arm 95 a fixed extent from its idle position to cause lug 100 on said arm to rock tappet bar 76 downward about its pivot 78 a fixed extent sufficient to free the lug 80 on lever 51 from shoulder 79 on the tappet bar before the mutilated pinion demeshes from segment rack lever 90. As soon as the demeshing of the pinion and rack lever occurs, the rack lever and the lever 86 and arm 95 all return instantly to normal position under the constant biasing force exerted thereon. If pressure is removed from the key before arm 95 disconnects shoulder 79 from lug 80, or when arm 95 disconnects this shoulder and lug with pressure maintained on the key, the spring 53 instantly restores lever 51 and latch arm 57 to their normal positions to render them effective to disengage the clutch dog 43 and hold it disengaged and to also lock the dog carrier 45 at

the end of a 360 degree driven rotation of the dog carrier from its normal idle position, thereby also locking the mutilated pinion 47 in its normal position after a 360 degree rotation thereof. Springs 66 and 53 will restore the key lever and tappet bar to normal position whenever pressure is removed from the key. If pressure is removed from the key before arm 95 rocks tappet bar 76 out of engagement with lever 51, the springs 66 and 53 will restore the manually shifted parts 41—62—75—73—72—74—76 to idle position, but the clutch will nevertheless complete its cycle of operation and disengage.

The leftwardly extending arm of the bellcrank 105 is connected by an up and down extending link 108 with the pivot 94 carried by lever 86 of the clutch mechanism. The return springs 26 and 96 bias dog 20, arm 22, link 101, arm 104, bellcrank 105, link 108, lever 86, segment rack lever 90 and arm 95 to normal idle position, the idle position of said parts being determined by frame stops 88 and 27. The stop 88 is adjustably bendable up and down, and the push-pull connection between the dog 20 and lever 86 is extensibly adjustable at 107—108a. The stop portion 76 of key lever 62, and the lower portion of the pendent arm of said key lever, are both adjustably bendable fore and aft of the machine, and the stop portion 54 of lever 51 is also adjustably bendable fore and aft of the machine.

The embodiment of the invention shown provides an actuating train between the back spacing dog and the driven element of the normally disengaged cyclic clutch, which train is so constructed that power transmitted from shaft 36 through said clutch imparts a complete back spacing movement of fixed extent to the dog 20 to back space the carriage one letter space during each cycle of operation of said clutch, and also that a complete power-actuated vibrative or reciprocative cycle of operation of said dog 20 is effected substantially instantly and during each cycle of operation of said cyclic clutch.

During the first part of each cycle of operation of the clutch, the link 108 will be pulled down a fixed extent by power from shaft 36 and impart a fixed working stroke to dog 20, whereupon the link will rise and the dog will return to normal idle position during the latter part of the cycle of operation of the clutch. On its working stroke the dog 20, as in the known machine, rocks on its pivot until its teeth 25 mesh with the teeth of feed pinion 16 and then moves leftward to the end of the stroke to rotate pinion 16 to reversely drive the carriage slightly more than one letter space but less than two letter spaces. At the end of the working stroke of the dog, the cam edge 20b thereon rides on the framework adjacent the bottom of slot 24 to jam the dog between the bottom of said slot and the pinion and thereby prevent momentum of the carriage from moving the carriage reversely more than the desired distance. The slight excess of back spacing movement of the carriage is for the usual purpose of insuring entry of the escapement dog 18 between the proper two teeth of the escapement ratchet wheel 15 before back spacing dog 20 starts its return stroke. On its return stroke, the dog 20 swings down out of mesh with the feed pinion which is then held again by the engagement of escapement dog 18 with ratchet wheel 15, as usual, and the dog 20 finally moves rightward to idle position.

It will be observed that the construction shown and described provides for very rapid successive

back spacing operations since the back spacing dog has a full and exactly predetermined working stroke imparted to it during the first half (or slightly more) of each revolution of the driven element of the single-revolution clutch and returns to normal position during the remainder of the revolution of said element, which element is in turn rotated by the high speed power shaft.

The improved construction also provides means which can readily be constructed and adjusted to impart exactly the desired back spacing throw to the back spacing dog and instantly return it to idle position, avoids the use of a slip clutch as well as difficulties inherent in attempting to control the throw of the dog by duration of clutch engagement, and provides for actuation of the dog on its working stroke by power transmitted from a high speed power shaft by a positive clutch and for return of the dog by spring means.

We claim:

1. In a typewriting machine, a back spacing mechanism comprising, in combination, a back spacing dog, a reciprocative rack positively connected with said dog, means biasing said dog and rack to a normal idle position, a power shaft which is journaled in the machine and is constantly rotated while the machine is in use, a mutilated pinion loose on said shaft, and a single-revolution positive clutch mechanism for coupling said mutilated pinion with said shaft for a single revolution of the pinion from a normal idle position to cause the pinion first to mesh with the rack, then to drive the rack a fixed extent in opposition to its bias to impart a fixed working stroke to the dog, and finally to demesh from the rack prior to completion of said revolution and remain demeshed until the next revolution of the pinion.

2. In a typewriting or like machine having a carriage back spacing element mounted therein for working and idle return strokes respectively from and to a normal position in which said element is disconnected from a reciprocal carriage which is advanceable under control of an escapement, means for actuating said element on its working and idle return strokes comprising, in combination, a shaft which is constantly rotated by power while the machine is in use, a mutilated pinion, means to connect the shaft with the pinion to drive the pinion through a single revolution only and to thereupon automatically disconnect the shaft and pinion and arrest the pinion in a normal idle position thereof, a reciprocal rack drivable from a normal idle position by said pinion during each revolution of the pinion by the shaft, said pinion being so toothed as to mesh with said rack during only an intermediate portion of each revolution of the pinion, means to drive said element on its working stroke through the medium of said rack while said pinion is in mesh with the rack, and means for constantly biasing said element and rack to move to their respective normal idle positions.

3. In a typewriting or like machine having a conversely movable member drivable in one direction to back space a reciprocal carriage which is positively connected with said member and is advanced under control of an escapement, power actuated means for driving said member one step at a time in said one direction comprising, in combination, a mutilated pinion rotative about a fixed axis, key-controlled power means for cycling said pinion through a single revolution and arresting the pinion in a normal definite stop position each time the control key of said power

means is actuated, biased driving means for said member movable in opposition to its bias to drive said member in said one direction and movable under its biasing influence to disengage from said member and return to a normal idle position, and stop means to arrest biased movement of said driving means at a point at which the driving means is disconnected from said member and pinion, said driving means including a reciprocal rack with which said pinion first meshes and then demeshes once during each revolution of the pinion to first move said biased driving means in opposition to its bias and to then permit biased movement of said driving means to the normal idle position thereof determined by said stop means.

4. In a typewriting or like machine having a toothed element which is conversely movable in response to retraction and escapement-controlled advance of a reciprocal carriage of the machine, key-controlled power actuated mechanism for actuating said element to back space the carriage comprising, in combination, a driving clutch element which is constantly rotated about a fixed axis while the machine is in use, a driven clutch element biased to engage the driving clutch element, means rotative about said axis and carrying said driven clutch element, means biased to disengage the driven clutch element from the driving clutch element and hold the driven clutch element and said rotative means in a definite stop position thereof against rotation in both directions about said axis, a key-operated tappet device biased to a normal position and movable by finger pressure to move and hold said biased means against its bias out of operative position, means operable by said rotative means to temporarily disconnect said tappet device from said disengaging and holding means once during each revolution of said rotative means, biased impelling means for said toothed element engageable and drivable in opposition to its bias by said ro-

tative means during only an intermediate portion of each revolution of said rotative means to impel the toothed element in carriage back spacing direction and movable by its bias to a normal idle position when disengaged from said rotative means, and stop means for arresting biased movement of said impelling means.

5. In a typewriting or like machine having a reciprocal carriage advanceable under control of an escapement, key-controlled power actuated mechanism for back spacing the carriage comprising, in combination, a clutch having driving and driven elements biased to engage, power means for constantly rotating the driving clutch element while the machine is in use, means biased to disengage the clutch elements and arrest the driven clutch element in a single definite stop position, a key-operated device biased to a normal position from which it is movable by finger pressure to move and hold said biased means against its bias in a position permitting engagement of the clutch elements and rotation of the driven clutch element, means operable once by each revolution of the driven clutch element to back space the carriage, and means operable by revolution of the driven clutch element to temporarily render said key-operated device ineffective on said biased means once during each revolution of said element.

6. A typewriting or like machine, as claimed in claim 5, wherein the means operable once by each revolution of the driven clutch element to back space the carriage comprises a member connected with the driven clutch element to rotate in unison therewith, and a reciprocal member biased to a normal idle position and engageable and drivable in opposition to its bias by said rotative member during only an intermediate portion of each revolution of said driven clutch element and said rotative member to back space the carriage.

CHARLES WALKER.
WILLARD H. WADE.
